UNITED STATES PATENT OFFICE

JERROLD LOEGL, OF CHICAGO, ILLINOIS, ASSIGNOR TO JOHN R. THOMPSON CO., OF CHICAGO, ILLINOIS, A CORPORATION OF WEST VIRGINIA

DESIGN FOR A TABLE TOP

Application filed February 28, 1930. Serial No. 34,705. Term of patent 14 years.

To all whom it may concern:

Be it known that I, JERROLD LOEGL, a citizen of the United States, residing at Chicago, in the county of Cook and State of Illinois, have invented a new, original, and ornamental Design for Table Tops, of which the following is a specification, reference being had to the accompanying drawings, forming part thereof.

I claim:

The shading in the drawing is for the purpose of illustrating two zones of contrasting shades.

The ornamental design for a table top, as shown and described.

JERROLD LOEGL.
